UNITED STATES PATENT OFFICE.

PETER R. GONSKY, OF DETROIT, MICHIGAN, ASSIGNEE TO ENDLESSGRAPH MANUFACTURING COMPANY, A CORPORATION OF NEW JERSEY.

COMBINED TABLE LIGHT, FAN, AND PHONOGRAPH

1,259,053.

Specification of Letters Patent. Patented Nov. 16, 1920.

Application filed November 14, 1917. Serial No. 202,829.

To all whom it may concern:

Be it known that I, PETER R. GONSKY, a citizen of the Dominion of Canada, residing at Detroit, in the county of Wayne and State of Michigan, have invented certain new and useful Improvements in Combined Table Lights, Fans, and Phonographs, of which the following is a specification.

The invention has for an object to provide a construction in a stand and mechanism whereby the appliance may be used as a gramophone, fan and reading light, combined, adapted to be set upon any suitable horizontal surface, and utilized for its various functions in an efficient manner, without interference of one with another. It is an important object to give a construction of this character in which the shaft for the rotating table of the gramophone may be employed to rotate and drive the fan, and an additional interposed flexible shaft connection employed, without interfering with the proper use of the appliance for the rapid emplacement and removal of the record disk. A further aim is to give novel improvements in the structural details and elements of an appliance of this character, whereby its manufacture will be facilitated, its use made efficient, and its action also. A further important aim is to utilize a lamp-motor base as a sound amplifier. Another important aim is to give a novel means for raising and lowering a fan connection from engagement with the gramophone main shaft.

Additional objects, advantages and features of invention will appear from the construction, arrangement and combination of parts hereinafter set forth and shown in the drawings, wherein,

Figure 1 is an elevational view of one embodiment of my invention,

Fig. 2, is a detail of a flexible shaft connection.

There is illustrated a motor casing comprising a base 10, substantially in the form of the ordinary lamp base, having an attenuated grip portion 11 intermediately of its height, and being flared outwardly and downwardly toward its lower part, and formed with a reinforcing rim 12 carrying balls or feet 12' adapted to rest upon any horizontal surface. The base also includes an upper casing portion 13 in the form of an inverted bell. A motor 15 is provided adapted to fit snugly within the cylindrical portion 14 of the casing, which opens up-

wardly. The motor has a lower casing portion 16 on which suitable terminals 17 are provided for making connections with the motor. The motor shaft 18 is supported by a ball thrust bearing 19 carried in a suitable block 20 threaded in the lower part of the casing element 16. The upper part 15' of the motor casing is enlarged sufficiently to accommodate a friction disk 20^a, and in addition to a bushing for the shaft 18, has in its upper part a hollow shouldered cylindrical bearing 21^a, freely revoluble on which there is a suitable turn table 21 upon which a gramophone record 22 may be disposed. In the ordinary way, the shaft 18 projecting upwardly through the bearing 21^a a suitable distance to engage through the customary central opening of the record. Upon the disk 20^a there rests a friction wheel 25, carried slidably upon a horizontal stud shaft 26, the friction wheel 25 being adapted to be reciprocated upon the stud shaft 26, the casing element 15' being slotted at its upper side to permit such movement and to permit coengagement of the friction wheel with the disk 20^a. The friction wheel is provided with a hollow shaft 23 with friction surface 24, bearing at its upper side upon the under surface of a flange 21' on the table 21, so that the latter will be rotated at a slow speed through the agency of the friction wheel 25. The shaft 26 is threaded at its outer part, and slidably thereon is a suitable sleeve 27 engaging the outer end of the shaft 23 whereby movement of the sleeve inward will move the wheel 25 longitudinally on the shaft 26. The sleeve is engaged by the inner end of a speed adjusting knurled nut 28 engaged on the shaft 26 on its outer end for manipulation to regulate the speed of the table 21. Outward movement of the wheel 25 will be caused by its tangential traction on the table, when the nut is unscrewed. It will be readily understood that the nearer the center of the disk 20^a the wheel 25 may be disposed, the slower the speed of the table 21, and likewise, the further outward the wheel 25 may be moved the more rapidly the table 21 will rotate.

The base 10 has lateral tubes 30 and 30' through which passages 31, 31', lead into the interior of the base 10, just above the neck 11 which has a clear space therethrough communicating with the enlarged space within the base at its lower part. The upper ends of the tubes are vertical and pro-

ject a distance above the record table 21 and laterally outward thereof. A canopy 32 is provided having legs 33 disposed slidably in the upper ends of the tubes 31. The legs 33 are extended from a bearing block 34 having a suitable vertical bushing 34' therein in which a shaft 35 is rotatable and vertically slidably, this shaft being provided with fan blades 36 carried upon suitable 10 arms extended radially from the shaft, the blades being slightly canted forward at the upper sides in the direction of rotation, so that air is directed downwardly to a slight extent thereby. The shaft 35 is supported 15 revolvably upon a head 37, resting upon the bearing 34' by which the shaft may be raised and lowered. A number of lamp sockets and lamps 38 are carried by any approved construction on the block 34, wiring for 20 which is diagrammatically illustrated at 42, extending through one leg 33 into the passage 31' through which it is carried into the base 11 and outwardly therefrom in any desired manner. Upon the rectilinear portion 25 of the tube 31 immediately above the table 21 a collar 46 is secured, forming a rest for the vertically bored base portion 47 of a sound arm 48 revolvable upon the pipe, the pipe being slotted at the side adjacent the 30 table 21 for communication with the passage in the sound arm 48. A sound box and needle mounting 49 are mounted upon the outer swinging end of the arm 48, in accordance with well known practice.

35 The shaft 35 is formed with peripheral annular grooves 51 and 51' respectively, spaced longitudinally of the rod, a spring pressed pin being provided in the block 34 bearing against the shaft 35 for alternative 40 engagement in the grooves, the latter being rounded at their sides and the inner end of the pin being suitably rounded so that the rod will be yieldably held by the pin at respective limits of its vertical movement.

45 The lower end of the shaft 35 is socketed to receive the upper end of shaft 18, the latter being slotted, as at 45 and a key pin 44 being provided in the socket.

In use, when it is desired to place a record 50 in position, the sound arm 48 is swung to one side and the shaft 35 is raised to uppermost position by lifting the knob 37 and after emplacement of the record pressure on the knob will lower the shaft 35 until its 55 clutch portion engages with that of the shaft 18. The motor being in operation, and the speed approximately regulated to the desired extent, the sound arm is swung inwardly and the needle adjusted upon the 60 record in the customary manner. Removal of a record will be understood from the foregoing description. In the event that it is desired to use the device to drive small household appliances, such as massage vibrators, a small bevel gear 60 is provided,

having a downwardly extending sleeve portion 61 adapted to engage snugly around the shaft 18 and provided on its interior with suitable lugs 62 to engage in the socket 45 of the shaft 18, the upper side of the lugs 70 being provided with a stud shaft recessed in the same manner as the upper end of the shaft 18, as shown at 64. Meshed with the gear 60 there is another gear 66, connected in a familiar way with a flexible shaft of 75 any suitable character, carried in the customary casing 67. The gears are held in operative relation by means of a yoke 68 as shown. By adjusting the gear 60 upon the upper end of the shaft 18 the fan shaft 80 may be lowered into engagement with the stub shaft on the upper side of the gear so that the fan and phonograph may be operated simultaneously with the driving of the flexible shaft.

By canting the blades of the fan so that air is directed downwardly toward the table, air engaging the table will be checked and caused to move laterally outward, producing a current of air of a radiating form 90 in a plane on a level with the table, the displaced air being replaced from above and below.

What is claimed:

1. A combined phonograph and fan comprising a vertical revoluble shaft, a concentric table therearound rotatably mounted and operatively connected with the shaft, means to rotate the shaft, a vertically adjustable shaft above the first shaft, a fan 100 operatively associated with the vertically adjustable shaft, means to connect the two shafts when the vertically adjustable shaft is in its lowermost position, and means to support the adjustable shaft in raised position.

2. In a device of the character described, a support, a motor mechanism therein, a centrally apertured record table operatively connected with the motor, a motor driven 110 shaft concentric with and separate from said table, a vertically adjustable shaft thereover constructed for coengagement with the first named shaft, a support for the vertically adjustable shaft comprising a tubular element extended upwardly from said support, a sound arm revolvable on the tubular element, said tubular element being apertured for communication with the interior of the sound arm, said support including 120 a hollow casing element in communication with said tubular element, and constructed for magnification of sound.

In testimony whereof I have affixed my signature in presence of two witnesses.
